UNITED STATES PATENT OFFICE.

GILMAN WOODWARD AND FRANKLIN S. HATHAWAY, OF KEENE, NEW HAMPSHIRE.

SECURING GARMENTS TO HOOKS.

Specification of Letters Patent No. 22,996, dated February 15, 1859.

To all whom it may concern:

Be it known that we, GILMAN WOODWARD and FRANKLIN S. HATHAWAY, of Keene, in the county of Cheshire and State of New Hampshire, have invented a useful Device for Securing Garments and other Textile Fabrics to Hooks; and we do hereby declare that the following is a full and exact description thereof, reference being had to the accompanying drawings and to the letters of reference marked thereon.

The nature of our invention consists in securing a hook to a sliding plate for the purpose of causing an arm to fall upon the head of the hook by means of a weight being suspended therefrom, or by other means forced downward and securing the same in its position, also in providing the arm and hook at their points of contact with spurs for the purpose of retaining any article of textile nature that may be secured therein.

To enable others skilled in the art to make and use our invention we will proceed to describe its construction and operation.

25 The device herein described is intended to be secured in a vertical position by the back plate H¹, as is shown by the different sections and elevations of the drawings. The hook B¹ is secured at its base to the sliding plate C, C, which is fitted to the channel i i² in the back plate H¹ and is secured thereto by the ears l, l, l, l² in a manner to allow its free upward and downward motion. The arm F¹ is attached to the top of said sliding plate by the pivot c. At the heel of said arm are the teeth r, r, which mesh into the cavities i, i in the back plate H, by which means the arm F is actuated by the sliding plate C, C. The tumbler S² is pivoted at m to the sliding plate C, C¹ within its cell g² at the base of the hook B¹. The block d¹ is secured to the back plate H¹ and projects forward into the tumbler-cell g² occupying the groove u¹, the arm F being elevated as shown in Fig. 1. An article of sufficient weight suspended from the hook B will cause the arm F to descend upon the head of said hook, in which position it is secured by the tumbler S² which falls under the block d, actuated by the spring t. The tumbler S is beveled at its head for the purpose of compensating in its securing points for the different thicknesses that may be interposed between the

head of the hook B¹ and the point of the arm F. A garment or other article of a textile nature being thus interposed is prevented from being drawn therefrom by the means of the spurs d, b, as shown in Fig. 3. The spur d is secured within a slot at the point of the arm F¹ by the pivot c³ in a manner to allow the desired limit to its motion. The spur b is secured in a similar manner at the head of the hook B¹, the relative positions being such that their rear projections act in counter point. The article thus secured is relieved by passing the key j¹ upward through the key hole o, in the base of the hook B till the wing a strikes the projection v of the tumbler S² when a partial turn of the key j¹ will force the tumbler S² back to a vertical position, disengaging the head of the tumbler from the block d². The hook B¹ being relieved of its weight, the sliding plate is drawn upward by the spring z, by which means the arm F is elevated and the article 75 upon the hook relieved. The key j being turned back and withdrawn leaves the tumbler S— resting against the side of the block d¹.

It will be seen by referring to the drawings and model that this device is not only intended to secure articles of a textile nature between the point of the arm and the head of the hook, but any article that may be passed over the head of the hook and suspended from the inner curve or otherwise embraced therein in form of a loop or ring.

What we claim is—

1. Securing the hook B, to the vertical sliding plate C, C, in the manner and for the purposes described and set forth.
2. The manner of operating the arm F, in combination with the movement of the hook B, and sliding plate C, C.
3. Arming the hook B, and the arm F, at their points of contact with moveable spurs in a manner and for the purposes described and set forth.
4. The tumbler S, when operated or described or otherwise to produce the same effect as specified and set forth.

GILMAN WOODWARD.

FRANKLIN S. HATHAWAY.
